LOADING AND TRANSPORTATION OF
MERCCHANDISE

Albert F. Pagel, Park Ridge, Ill., assignor to Sigma
Steel Strapping Company, Chicago, Ill., a
corporation of Delaware

Application May 21, 1936, Serial No. 80,992

9 Claims. (Cl. 105—369)

My invention relates to the loading and transportation of merchandise.

It is particularly applicable to merchandise which is packaged in horizontal layers and will be illustrated and explained in connection with the loading and transportation, on the floor of railway cars, of sheet material such as tin plate, for which it has been found particularly advantageous.

10 The so-called "shifting load" method of transporting merchandise is an accomplished fact. In general, it has given satisfactory results for several years. What is termed quite generally the "controlled shifting load" method, examples 15 of which are set forth in Ricketts and Moon Patent No. 1,988,513; January 22, 1935, and Scales Patent No. 1,920,917; August 1, 1933, has been found to be a decided improvement in connection with some types of merchandise and under some 20 conditions.

25 The shifting load method contemplates the binding of the merchandise into groups or units which, instead of being fixed relative to the vehicle, are permitted to shift freely except for the retarding effect of inertia and friction between the vehicle floor and the load unit. The "controlled shifting load" method contemplates the control of the shifting of units by the interposition of additional resistance to movement,— 30 not a resistance that will or can prevent shifting of the units under shocks, jars and strains incident to travel, but such as will ordinarily insure against excessive movement.

35 Some types of merchandise, such as relatively smooth and slippery sheet material, of which tin plate is a typical example, present particularly troublesome handling and transportation problems. Some of these problems have been satisfactorily solved by the shifting load and controlled shifting load methods. One problem, however, has not heretofore been solved with the degree of satisfaction desired, viz., the internal shifting between sheets constituting a pile or stack which, singly or in bound-together 40 groups, may constitute a load unit. Such internal shifting usually manifests itself in the longitudinal (i. e., lengthwise of car) tilting or skewing of the sheet stacks or piles. When movement occurs between sheets of a pile or stack of, for 45 example, tin plate, the sheets may be scratched and damaged or completely ruined by interposed particles of dust, etc. And even when there is no foreign matter between the sheets the mere rubbing of the sheets one upon another causes 50 the thin layer of tin to be worn thinner or en-

tirely through, exposing the underlying base metal or "black iron", usually in small spots commonly termed "black specks" and thereby rendering the sheets unsightly, unsatisfactory for use in food containers, and otherwise of inferior 5 quality. Tin plate is graded for acceptability by the number of "black specks" per unit area and it is consequently highly desirable both to the purchaser and to the consumer that such "black specking" be kept to a minimum. Even with the 10 most improved methods heretofore available, the loss from "black specks", resulting from lower-grade classification or utter unfitness for the contemplated use, has been many thousands of dollars per year.

15 One of the objects of my invention is to provide an improved method and means for facilitating the loading and safe transport of merchandise,— especially merchandise of the smooth sheet variety, such as tin plate.

20 Another object is to provide a method of preparing load units for shipment, particularly in railway cars, so as to reduce the amount of internal shifting in stacks or piles of sheet material, such as tin plate.

25 Another object is to reduce the tilting of the stacked sheet material (particularly tin plate) during transit.

30 Another object is to provide an improved load unit particularly adaptable for the shipment of stacked sheet material by shifting load methods.

35 Other objects and advantages will hereinafter appear.

A typical example of the application of my invention to the shipment of tin plate in piles or 35 stacks is illustrated in the accompanying drawings, wherein:

Fig. 1 is a perspective view of one end of a box car containing a load unit of tin plate stacks or packages arranged therein according to the preferred embodiment of my invention;

Fig. 2 is a slightly enlarged section on the line 2—2 of Fig. 1;

Fig. 3 is a perspective of the interior of one end of a box car during an initial stage in the preparation of a load unit in accordance with my invention;

Fig. 4 is a perspective of a typical package of tin plate such as may constitute a sub-unit of a load prepared in accordance with my invention, 50 and

Fig. 5 is a vertical longitudinal cross-section of a portion of a load unit embodying a slight modification.

Referring first to Fig. 4 which shows a typical 55

package or load sub-unit, the sheets 10, such as tin plate, are stacked or piled flatwise upon a support or, as it is usually termed, a "skid" 11. This skid consists of a plurality of runners 12 and a platform 13 mounted upon and secured to the runners by suitable means, such as nails or screws. Preferably both platform and runners are made of wood. The sheet stack, which may be built up to the desired height, and the skid are tightly bound together by flexible metallic binders 14 which are looped about the stack and skid—preferably parallel to the skid runners—then tensioned to the requisite degree and finally made into permanent package-encircling loops by securing together, with a suitable seal-joint 15, the overlapping ends of each binder loop. Experience has shown that, for example, tin plate sheets of a size about 20" x 28" piled to a height of approximately 14", can be satisfactorily bound to a skid by two $\frac{5}{8}$ " x .020" cold rolled steel bands. A package thus formed has an overall height of about 18" and a weight of about 2200 pounds. If desired, the corners and ends of the stack may be protected by pads 16 of thin sheet metal, fiber, fabric or heavy paper; or, if desired, the stack of sheets may be entirely encased in an envelope or covering of paper, cardboard or other suitable material.

Referring now to Figs. 1 and 2, the typical load unit selected to illustrate the explanation of my invention consists of eighteen packages or sub-units arranged in three longitudinal rows of six packages or sub-units per row. In addition to the group of packages or sub-units, each load unit consists of a bulkhead 20, located at the end remote from the car doorway, and a braced end gate 21 located at the opposite or doorway end of the unit.

Bulkhead 20 may be constructed in the usual manner and of any appropriate material. I prefer, however, to fabricate it from two parallel spaced horizontal transverse buttresses 22 of about 2" x 6" lumber cut to a length slightly greater than the transverse dimension or width 45 of the unit, and a number of upright spacing and reinforcing cleats 23 of about 1" x 6" lumber. Some of these cleats may be cut to a length substantially equal to the height of the sheet stack plus the thickness of the skid platform, while 50 others should be long enough to act as legs when they stand on the car floor to support the bulkhead. These horizontal buttresses and upright cleats may, preferably with the cleats on the inside next to the stack, be secured together, by 55 nails or other appropriate fasteners, to make a unitary bulkhead adapted to abut the end of the load unit remote from the car door.

The braced end gate at the opposite or doorway end of the unit includes a bulkhead composed of horizontal spaced buttresses 25 and upright cleats 26 essentially of the same construction as those constituting the bulkhead at the opposite end of the unit. The bulkhead is supported upon and held upright against the adjacent end packages by one or more brackets,—two such brackets being shown in Fig. 1. Each bracket includes a bottom member 27 which has one end insertable beneath the skid platform of an end package—parallel to and preferably 65 rather close to one of the package skid runners 12—and the other end projecting outwardly beyond the end of the package, as most clearly shown in Fig. 2. My preferred bracket also includes an upright 28 which rests endwise upon 70 bottom member 27, a horizontal chord or pres-

sure member 29 which lies flatwise upon the projecting portion of bottom member 27 and extends from the outer side of upright 28 to the end of bottom member 27, and a diagonal brace 30 which extends from the upper end of upright 28 to the outer end of chord or pressure member 29. Such a construction is preferred because it can be fabricated from sizes of lumber available to most shippers. Preferably the ends of diagonal brace 30 are formed, such as by beveling them, so as to abut, throughout the cross-section, against pressure or chord member 29 and upright 28 respectively. Such brackets may be made of wood or other suitable material appropriately secured together, by screws, nails or other appropriate fasteners, so that it can be handled as a unit. When thus assembled the upright 28 serves as an abutment for the adjacent bulkhead, the chord or pressure member 29 and diagonal brace 30 serve as abutments to reinforce the upright against displacement and the diagonal brace together with the tensioned binder hereinafter described act to prevent the upright—and consequently also the bulkhead—from hinging or tilting in either direction about the lower end relative to the bottom member. And when the inwardly projecting end of the bracket bottom member 27 fits rather closely into the space between the skid platform and the car floor it is reinforced or braced against tilting by the heavy package thereabove and the car floor therebelow. I have found that such brackets fabricated from 2" x 6" lumber cut to proper length and shaped and nailed together produce satisfactory results.

The assembly of packages is tightly bound together between the rear bulkhead 20 and the front braced end gate 21 by one or more longitudinal flexible metallic binders,—there being at least one binder for each end gate bracket. In Fig. 1 there are shown three longitudinal binders 35, 36, 37. In looping binders 35 and 37 about the load they are passed not only about the group of packages and bulkhead 20, but also along bottom members 27 and diagonal braces 30 of the end gate brackets so that when they are tensioned they clamp the uprights of the brackets tightly against the front end bulkhead. Preferably the forward end of each bottom member 27 is beveled, as at 38, which, together with the exposed end of chord member 29, affords the effect of a rounded corner for the passage of the binder. A somewhat similar rounded effect is provided by the upper end of the diagonal brace abutting at an angle the top of the bracket 50 upright. Such rounded corner effects are of advantage because they help to insure a more uniform distribution of the binder tension, which is usually applied by a suitable tool in the top horizontal reach and otherwise might be unduly concentrated there. A protector strip 39, of 55 rather light gage sheet metal, may be bent around the forward lower corner of each bracket below the binder, to further facilitate the distribution of the binder tension and to serve as a protection 60 when the unit shifts in the car during transit. The intermediate longitudinal binder 36 is merely looped and tensioned about the group of packages and the two end bulkheads and then made permanent by joining its overlapping ends in any 65 approved manner.

As described, the tensioned binder passes under and around the outer end of bottom member 27, the adjacent outer end of the pressure member 29 and the lower end of brace 30, then along 70

brace 30 and over the upper end thereof, thereby preventing longitudinal movement of these three elements away from the package and preventing any shifting or separating movement of brace 5 30 and chord 29 away from bottom member 27. The car floor beneath and the load unit above prevent anything but longitudinal movements in bottom member 27. Thus any pressure of the load unit against any portion of upright 28 causes 10 a direct force against the binder where it passes about the braced end gate and, by means of the binder, an exactly similar force is applied to the lower portion of the opposite end of the load unit through the end bulk head 20. The 15 top of the bundle is thereby prevented from shifting to the left as viewed in Figure 2, relative to the lower edge of the unit. Similarly any outward force against the upper portion of bulk head 20 (such as would occur if the load constituents or sheets in the upper region of a package try to shift or move to the right relative to lower sheets therein) results in a direct pull on the binder over the top of the unit and thereby against the outer ends of brace 30 and pressure 20 member 29 and is thus translated into exactly similar force against the opposite end of the unit through upright 28. In other words, both bulk heads are maintained tightly against the ends of the load unit and, in the specific embodiment 25 illustrated in the drawings, substantially perpendicular to the car floor regardless how much the unit as a whole may shift during transit. Thus the upper portion of each sub-unit or package is prevented from shifting relative to the lower 30 portion thereof, either to the right or to the left as shown in Figure 2, by the action of the tensioned binder and the braced end gate and internal shifting or tilting is effectively prevented.

If desired—and I have found it to be of some 40 advantage in connection with tin plate shipments—side or longitudinal bulkheads 40 and 41 may be used along the sides of a load unit. These longitudinal bulkheads, which can be constructed in the same manner and of the same material 45 as the end bulkheads heretofore described, are held in place by flexible metallic tensioned cross binders 42. Preferably these cross binders, in the reaches below the load unit, should lie above the lower floor-contacting surfaces of the longitudinal binders and this end may be readily attained by locating the cross binders so that they lie in the spaces between the ends of the skid runners of longitudinally adjacent packages or sub-units, as most clearly shown in Fig. 2. Preferably, also, the side bulkheads should be provided with an upright cleat where the load unit is encircled by a cross binder.

I have found that longitudinal binders of 2" x .050" cold rolled steel strap and cross binders of 1 1/4" x .035" cold rolled steel strap give satisfactory results with units of the size and character heretofore described.

In preparing the end of a car for the reception of a load unit, the longitudinal binders 35, 36 and 65 37, preferably cut to a length somewhat in excess of that required completely to encircle longitudinally the assembled load unit, are first laid longitudinally along the car floor in the space to be occupied by the load unit, as shown in Fig. 3. The length of the binders necessary to complete the loop about the load unit may be temporarily coiled and attached to the end wall of the car by staples 45 or other means. If load-shift controlling means such as set forth in the heretofore 70 mentioned Ricketts and Moon patent or the

5 Scales patent are to be used, they should be applied as explained in those patents before the load is completely assembled. Next, the cross binders 42, preferably cut to a length somewhat in excess of that required completely to encircle transversely the assembled load unit, are draped transversely across the floor of the car and overlying the longitudinal binders. The length of each cross binder necessary to complete the loop about the load unit may likewise be temporarily 10 coiled and attached to the side wall of the car by staples 45 or other means.

15 After the space a load unit is to occupy in the car has been thus prepared—commonly called “draped”—the bulkhead 20 is placed in the far end of the car. For convenience it may be stood against the end wall of the car. Then the desired number of packages or sub-units are placed in the car—or, if desired, assembled in the car—over the horizontal reaches of the longitudinal 20 and cross-binders which lie on the floor and with their skid runners arranged longitudinally of the car floor. In Fig. 3 five of the eighteen packages or sub-units are shown in place. When the requisite number of packages to complete the 25 group or load unit have been placed, the end gate 21 is positioned against the car door end of the group. This is conveniently accomplished by first inserting between the skid platform and the car floor the inner ends of the bottom members of 30 the requisite number of brackets and sliding them under the packages until the bracket uprights are quite close to the ends of the packages,—close enough merely to leave clearance for the bulkheads to be slid down between the uprights and 35 the ends of the packages. Then the ends of each longitudinal binder are brought together at the top of the load unit, the binder loop is tensioned by a suitable tool, and finally the ends of the loop are joined to make the loop permanent. Those 40 longitudinal binders which align with end gate brackets are trained along the bottom members and diagonal braces thereof as hereinabove explained, before they are tensioned. The tensioning of the longitudinal binders causes the two end 45 bulkheads to be drawn toward each other. And, since the bulkhead at the braced end gate is prevented from tilting by the bracket bottom member (which, in effect, telescopes under the load), and the diagonal brace tensioned binder, the load 50 unit is tightly clamped between them—and the load sub-units are bound together—about as though the bulkheads were the vertically parallel jaws of a vise,—a vise that forms a part of and moves with the load as it shifts under the 55 jolts and jars of transit.

In other words, the tensioned binder at the braced end of the load, acting at the apex of an angle the base of which is the vertical bulk head, not only serves to bind the load constituents together but, particularly through the pressure member, and brace, exerts an inwardly directed thrust against the vertical bulk head in both its upper and lower regions; and, through the additional action of the bottom member, the load 60 cannot tilt in either direction without stretching and enlarging the tensioned binder loop which, of course, should be made strong enough effectively to resist the load tilting forces encountered under ordinary conditions of transportation. In order 65 to bind together the constituents of a load unit, it is usually the better practice to tension simultaneously two binders on opposite sides of the center of the unit.

70 After the longitudinal binders have been thus 75

applied to the load unit—or before, if desired—the cross-bindings are similarly looped, tensioned, and made permanent about the unit.

Fig. 5 shows a slight modification in the construction of the bottom member of the end gate bracket,—a modification which may be used when the depth or height of the package skid runners is greater than the standard depth or height desired for the bracket bottom member. Thus, for example, if the standard bracket bottom member 27' is made from 2" x 6" lumber disposed flatwise relative to the car floor and the skid runners 12' are also made of 2" x 6" lumber disposed degewise relative to the car floor, there would be a space 15 of four inches between the top of the bottom member and the under surface of the skid platform. This gap might be objectionable because it would afford the bracket bottom member some opportunity to tilt—perhaps excessively—since it 20 would not be immediately reinforced and braced vertically on opposite sides by the heavy package and the car floor. This possible difficulty can be overcome by attaching a suitably dimensioned filler piece 50 to the top of the inwardly projecting portion of the bracket bottom member 27'.

While I have illustrated and explained my invention as employed in the preparation of load units consisting of a group or assemblage of packages or sub-units which themselves are assemblies of still smaller sub-divisions, it will be readily understood that it may be equally applicable where each sub-unit is an individual merchandise element. For example, the sheet material may be of such large dimensions that a 35 single stack or pile is sufficient to constitute a load unit. Under such conditions it may be advantageous—even necessary—to do all of the assembling in the car and to locate the end bulkheads and braced end gate directly against opposite 40 edges of the sheets constituting the stack, and themselves constituting the sub-units. Likewise, although I have illustrated and described the use of binders of only the flat strap variety, it will be readily understood that binders of round wire 45 and other cross-sectional shapes may be employed. Sometimes it may be advisable to employ braced end gates at both ends of the load unit, instead of only at one end, in which event the brackets at the end remote from the car door, which brackets 50 may be identical with the one heretofore described, should usually be set in position before any of the load is placed although, of course, after the space has been draped with the longitudinal and cross-bindings.

55 In addition to the decided reduction in, if not the practical elimination of, the rubbing together of the sheets, the prevention of the shifting of the sheets within a stack or pile results in other advantages. For example, if the stacks are enclosed or enveloped in cardboard or other fragile protective wrappings, the prevention of internal shifting keeps the sheets from puncturing the wrappings. Shift reduction also protects the edges of the sheets against injury. And where 60 sheets are fed from stacks by automatic machinery, as is often the case in the manufacture of tin cans, it is very important that the edges of the sheets constituting the stack align, i. e., that the stacks be straight, in order that the automatic feed may function properly.

Having thus illustrated and described the nature and a typical embodiment of my invention, what I claim and desire to secure by United States Letters Patent is as follows:

75 1. A load unit for transport in a vehicle in

shiftable relation thereto, comprising a plurality of supporting runners adapted to rest on the vehicle floor; a stack of sheet material piled flatwise upon the runners; an end gate abutting one end of the sheet stack, said end gate comprising 5 a bottom member lying partly beneath the sheet stack and projecting beyond an edge thereof, a vertical member carried by the bottom member and abutting an end of the sheet stack, and a diagonal brace extending between the projecting portion of the bottom member and the vertical member; and a flexible member looped and tensioned about the stack and end gate tightly to bind the stack and end gate into a unit which may shift bodily relative to the vehicle. 15

2. A load unit for transport in a vehicle in shiftable relation thereto, comprising a plurality of packages, each package comprising a plurality of supporting runners for resting on the vehicle floor, a stack of sheet material piled flatwise upon the runners, and a flexible member looped and tensioned about the stack to hold the sheets together; an end gate abutting one end of the group of packages, said end gate comprising a bottom member lying partly beneath one of the end 20 packages of the group and projecting beyond an edge thereof, a vertical member carried by the bottom member and abutting the end packages at one end of the group, and a diagonal brace 25 extending between the bottom and vertical members of the gate; and a flexible binder looped and tensioned about the group of packages and the end gate tightly to bind the packages and end gate into a unit which may shift bodily relative to the vehicle. 35

3. A load unit for transport in a vehicle in shiftable relation thereto, comprising a stack of sheet material piled flatwise; an end gate, said end gate comprising a bottom member lying partly beneath the stack and projecting beyond one edge thereof, a vertical bulkhead supported by the bottom member and abutting an end of the stack, and a diagonal brace extending between the projecting portion of the bottom member and the bulkhead; and a flexible binder looped and tensioned about the stack and the end gate 45 tightly to bind the stack and end gate into a unit which may shift bodily relative to the vehicle.

4. A load unit for transport in a vehicle in shiftable relation thereto, comprising a stack of sheet material piled flatwise; an end gate, said end gate comprising a bottom member lying partly beneath the stack and projecting beyond one edge thereof, a vertical bulkhead supported by the bottom member and abutting an end of the stack, a diagonal brace extending between the projecting portion of the bottom member and the bulkhead, and a chord member lying along the bottom member between the lower end of the diagonal brace and the bulkhead; and a flexible 55 binder looped and tensioned about the stack and the end gate tightly to bind the stack and end gate into a unit which may shift bodily relative to the vehicle.

5. A load unit for transport in a vehicle in shiftable relation thereto, comprising a stack of sheet material piled flatwise; an end gate, said end gate comprising a bottom member lying partly beneath the stack and projecting beyond one edge thereof, a vertical bulkhead supported by the bottom member and abutting an end of the stack, and a diagonal brace extending between the projecting portion of the bottom member and the bulkhead; and a flexible binder looped and tensioned about the stack and the end gate along the 70 75

bottom member and diagonal brace thereof tightly to bind the stack and end gate into a unit which may shift bodily relative to the vehicle.

6. A load unit for transport in a railway car in shiftable relation thereto, comprising a plurality of supporting runners resting on the car floor; a stack of flat metal sheets piled flatwise upon the runners; an end gate at one end of the sheet stack, said end gate comprising a bottom member lying beneath the sheet stack parallel to the runners and projecting beyond one edge of the stack, a vertical bulkhead supported by the projecting end of the bottom member and abutting an end of the sheet stack, and a brace extending between the projecting portion of the bottom member and the bulkhead; and a flexible metallic binder looped and tensioned about the sheet stack and the bulkhead along the bottom member and the brace thereof to bind the stack and bulkhead together as a unit shiftable as an entirety on the car floor.

7. A load unit for transport in a railway car in shiftable relation to the floor thereof comprising, a group of objects supported by parallel runners adapted to rest and slide upon the car floor; an end gate at one end of the group of packages, said end gate comprising a bottom member lying partly beneath the group of packages parallel to the runners and projecting beyond one end of the group, a vertical bulk head supported by the bottom member intermediate its ends and abutting one end of the group of objects, and a brace extending between the projecting portion of the bottom member and the bulk head; and a flexible metallic binder looped and tensioned about the group of objects and the end gate tightly binding the group and gate into a unit which may shift as an entirety upon the car floor.

8. A load unit for transport in a railway car

in shiftable relation to the floor thereof comprising, a group of objects supported by parallel runners adapted to rest and slide upon the car floor; an end gate at one end of the group of objects, said end gate comprising a horizontal portion which lies partly beneath and partly beyond an edge of the group of objects, a vertical portion which lies along and against one end of the group, and a portion which bridges between the horizontal and vertical portions; and a flexible binder looped and tensioned about the group of objects and the end gate tightly binding the group and gate into a unit which may shift as an entirety upon the car floor.

9. An end gate for use in the transport of merchandise load units on the floor of a railway car in shiftable relation thereto comprising, a bottom member having an inner end portion for insertion under the load unit between the load unit and the vehicle floor and an outer end portion which will project beyond the edge of the load unit when the inner end thereof is so positioned, an upright carried by the bottom member intermediate its ends and for abutting an end of a load unit lying above the inner portion of the bottom member, a pressure member lying upon the projecting outer end portion of the bottom member and at one end abutting against the lower end of the upright and at the other end coming substantially flush with the outer end of the projecting portion of the bottom member, and a brace extending between the upper region of the upright and the outer end of the pressure member, said brace and pressure member comprising means whereby the tension of a flexible binder bearing against the adjacent outer ends thereof may exert a thrust against both the upper and lower portions of the upright.
